METHOD AND APPARATUS FOR ERECTING HELICAL STORAGE VESSEL

Daniel J. Reed, Milwaukee, Wis., assignor to A. O. Smith Corporation, Milwaukee, Wis., a corporation of New York

Application March 5, 1953, Serial No. 340,438

10 Claims. (Cl. 29—429)

This invention relates to storage vessels and more particularly to a method and apparatus for erecting a helically wound silo from a series of suitable sheets of material.

An object of the present invention is to provide a simple and expedient method of erecting a helically wound silo whereby the labor costs are maintained at a minimum.

Another object of the invention is to provide an inexpensive apparatus for erecting a helically wound silo which may be readily assembled in the field with a minimum of joints and connections.

Still another object is to provide an apparatus which will unwind a metal sheet from a coil and progressively form the same into a series of helical convolutions.

A further object is to provide an erecting apparatus which has sufficient strength to support the entire silo and yet consists of a small number of lightweight pieces which may be readily assembled and packed for shipment to various erecting locations in the field.

Another object is to provide a method of erecting a silo which will substantially reduce the amount of both manual and mechanical handling of the material.

The ordinary metal storage vessel or silo is constructed from a number of rectangular steel plates which are individually squared, drilled, rolled to curvature and coated. Both in the field and in the shop a large proportion of the total labor is spent in the repeated handling of the multiple parts.

This inefficiency may be overcome by employing a helical-wound silo of the type described in the copending application of Erwin G. Dueringer Serial No. 337,701, filed February 19, 1953, entitled, "Storage Vessel" and assigned to a common assignee. This silo comprises a cylindrical body portion formed of a number of sheets which are helically wound in a series of overlapping convolutions. The trailing end of each sheet is bolted to the leading end of the following sheet, and the lower edge of each convolution is bolted to the upper edge of the following convolution to provide an integral substantially airtight body portion. A roof member encloses the top to the body portion, and the body portion is adapted to be supported beneath grade level by a foundation.

The present invention is directed to a method and apparatus for the erection of this helical silo and consists of a helical track carried by a supporting structure which rests on the silo foundation. The top sheet, in coiled form, is disposed on a reel or turntable adjacent the supporting structure, and a plurality of sheet carriers, which are adapted to ride on the track, engage the sheet. The sheet carriers are moved upwardly on the track by a hydraulic cylinder causing the sheet to progressively unwind from the coil and form into a series of helical convolutions. After the top sheet has been helically wound the remaining coiled sheets are successively disposed on the reel and progressively wound into helical form. The lower edge of each helical convolution is bolted or otherwise secured to the upper edge of the following convolution as each convolution is completed.

A vertical support disposed centrally of the supporting

2

structure supports the roof member and when the body portion has been wound to a sufficient height the roof is attached thereto.

After the entire body portion has thus been completed, the structure is backed downwardly on the helical track, with the hydraulic cylinder serving to limit the speed of the movement, until the structure rests on the foundation.

In the drawings:

Figure 1 is a perspective view of the completed helically wound silo;

Fig. 2 is an enlarged fragmentary perspective view of the lower portion of the silo, with parts broken away and sectioned;

Fig. 3 is a fragmentary vertical section showing the attachment of the body portion of the silo to the foundation;

Fig. 4 is a perspective view showing the assembly of the track, the radial supports and the center post;

Fig. 5 is a detail perspective view showing a track support unit and its attachment to the base ring;

Fig. 6 is a perspective view of the turntable employed to support the coiled sheets;

Fig. 7 is a perspective view showing the use of sheet hangers in initially unwinding the uppermost coiled sheet;

Fig. 8 is a perspective view showing the coiled sheets being wound in a helical manner and the attachment of the roof to the uppermost convolution;

Fig. 9 is a perspective view showing a sheet carrier mounted on the track and a hydraulic ram for advancing the sheet carrier; and

Fig. 10 is a longitudinal section of a sheet carrier mounted on the track.

Referring to the drawings there is shown an apparatus for the erection of a silo 1 substantially described in co-pending application Serial No. 337,701, filed February 19, 1953, and entitled, "Storage Vessel."

The silo as shown in the drawings comprises a generally cylindrical body portion which is enclosed at the top by a roof member 2 and supported beneath grade level by an annular footing 3.

The body portion of silo 1 is formed of a number of metal sheets 4 which are wound in a series of helical convolutions. To withstand corrosion, the sheets 4 may be coated with glass, plastic or the like.

The trailing end of each sheet 4 is bolted to the leading end of the following sheet and the lower edge portion of each convolution is similarly secured by bolts to the upper edge portion of the following convolution to provide the integral body portion of the silo.

Silo 1 is attached to footing 3 by clamps 5 which engage the inner base ring 6 of silo 1 and clamp the same to anchor bolts 7 which project upwardly from footing 3.

An annular unloader track 8 is secured to the inner surface of silo 1 approximately at grade level and carries unloader trough 9. A suitable conveyor unit, not shown, may be disposed within trough 9 and serves to convey the cut silage within trough 9 to the exterior of silo. Silo 1 is provided with a manway 10 which registers with trough 9 and serves as an exit for the removal of the cut silage.

A skirt ring 11 is inwardly spaced from silo 1 and extends downwardly from track 8 to footing 3. Ring 11 serves as a form for concrete supporting wall 12 which is poured into the annular space between silo 1 and ring 11.

The apparatus for the erection of silo 1 comprises, in general, a supporting fixture 13 which rests on footing 3 and carries a generally helical track 14. A turntable 15 is disposed adjacent the fixture 13 on grade level and serves to rotatably support the coiled sheets 4. A number of sheet carriers 16 removably engage the upper edge

portion of the free end of sheets 4 and are adapted to move on track 14 to progressively unwind the coiled sheets 4 and form the same into a series of helical convolutions.

Fixture 13 includes a base angle ring 17 which rests on footing 3 inside and adjacent the radius on which anchor bolts 7 are located. For ease of handling ring 17 may be formed of a number of arcuate segments each of which has a vertically disposed socket member 18 secured to the horizontal flange thereof. Adjacent segments of ring 17 are secured together by means of splice plate 19 to form the completed ring 17. The ring 17 may be temporarily secured in proper position by means of clamps 5, as shown in Fig. 4.

The track 14 is carried by a plurality of circularly spaced vertical track supports 20, as shown in Figs. 4 and 5, which include an outer supporting member 21 and an inner elbow supporting member 22 which is attached to the lower portion of outer member 21.

The lower end of each outer member 21 is adapted to telescope within the respective vertical cup member 18 and is locked therein by pin 23. The length of each vertical support 20 is progressively increased to enable track 14, which is carried by the supports 20, to be in the shape of an ascending helix.

Added rigidity and strength is provided for each support 20 by a pair of horizontal braces 24 which serve to join outer member 21 and inner elbow member 22. Suitable scaffold boards may be disposed across braces 24 to facilitate movement on the fixture 13 by the erection crew.

The upper end of outer member 21 carries an outer rail supporting bracket 25 while the upper end of elbow member 22 carries a vertically disposed inner rail supporting bracket 26.

Each of the supporting members 21 and 22 carries a pair of diagonal braces 27 which are pivotally secured at their lower extremities between a pair of brackets 28. Brackets 28 are welded to the respective members 21 and 22. The hinged attachment of diagonal braces 27 affords space saving for packing and shipment.

The helical track 14 is carried by vertical supports 20 of fixture 13 and comprises an outer rail 29 and an inner rail 30. Rails 29 and 30 are each constructed of an angle bar curved to the shape of a true helix. Outer rail 29 is provided with upwardly and inwardly extending flanges while the inner rail 30 has downwardly and outwardly extending flanges. For ease of handling rails 29 and 30 may be formed of a number of arcuate segments which are bolted together by means of splice plates 31 to form the rail.

The inwardly extending flange of outer rail 29 is bolted to the respective brackets 25, and additional support is given to rail 29 by the attachment of the free upper ends of diagonal braces 27 to suitable lugs disposed on the under surface of rail 29 intermediate the position of attachment of brackets 25 thereto.

The downwardly extending flange of inner rail 30 is bolted to the respective brackets 26, and the free ends of diagonal braces 27 are secured to the vertical flange of rail 30 by bolts.

The roof 2 is supported during assembly and attachment thereof to silo 1 by a vertically disposed tubular center post 32. Post 32 is supported at its lower extremity by a generally rectangular base plate 33 which rests on the ground within the annular footing 3.

The upper end of post 32 carries an umbrella-like support formed of an upper supporting ring 34 and a plurality of radially extending braces 35 which connect ring 34 to the post 32. Roof 2 of silo 1 is adapted to rest on ring 34 during erection of the silo.

Added rigidity is given to fixture 13 by radial supports 36 which serve to connect each vertical support 20 to center post 32.

Each of the radial supports 36 includes a central brace

37 which has the inner end thereof anchored to post 32 by suitable bolts while the outer end thereof telescopes, and is removably secured to, a tubular connection 38 which is attached to the central portion of the respective inner supporting members 22.

The attachments of the various central braces 37 to post 32 are positioned in the shape of a helix or spiral on post 32 to take into account the ascending helical contour of track 14.

Each radial support 36 is also provided with a pair of tubular braces 39. The inner end of each brace 39 is pivotally attached to brackets 40 which are welded to central brace 37. The outer or free ends of the upper braces 39 are removably secured by bolts to the brackets 26 attached to the upper extremity of elbow member 22 while the free ends of the lower braces 39 are removably secured between lugs 41 which are attached to the lower portion of members 22.

Sheet carriers 16 are adapted to ride on track 14 and successively engage and support the coiled sheets 4 and wind the same into helical form as the carriers move upwardly on the track. Each of the sheet carriers 16 includes a generally cylindrical body 42 which receives a plunger 43. The end of plunger 43 which is disposed within body 42 is reduced in diameter, and a spring 44 encircles the reduced portion of plunger 43. Spring 44 is interposed between the head of a stud 45 which is disposed within body 42 and the shoulder of plunger 43 to bias the plunger toward inner rail 30.

The exposed end of plunger 43 is bifurcated, and a horizontally disposed roller 46 is rotatably secured between the bifurcated arms of plunger 43 by bolt 47. Roller 46 rides on inner rail 30 and is provided with a circumferential groove which receives the outwardly extending flange of the rail 30.

The outer end of stud 45 projects outwardly from body 42 and extends through suitable openings in a pair of spaced roller brackets 48. A pair of rollers 49 are rotatably secured between the brackets 48.

Rollers 49 are vertically disposed and adapted to ride on outer rail 29. To prevent transverse slippage, rollers 49 are provided with circumferential grooves which receive the upper edge of rail 29.

The outer portion of sheet carrier 16 is prevented from lifting upwardly from rail 29 by a depending hook 50 which is secured to the inner side of outer bracket member 48 and extends downwardly therefrom. The lower portion of hook 50 is bent inwardly around rail 29, but out of contact therewith, and serves to maintain engagement of roller 49 with rail 29.

The outer end of stud 45 is adapted to engage a bolt hole in the upper edge portion of a sheet 4 and in co-operation with other studs serves to support the sheet as it is advanced and wound into helical form.

To limit the movement of plunger 43 within body 42, the plunger, as seen in Fig. 10, is provided with an outwardly extending pin 51 which moves within a slot 52 in body 42. When roller 46 is out of engagement with rail 30, plunger 43 is urged outwardly by spring 44 and pin 51 moves within slot 52 and strikes body 42 thereby stopping the outward movement of plunger 43 and preventing removal of plunger 43 from body 42.

To lock plunger 43 in a retracted position so as to facilitate the insertion of the sheet carrier 16 on the track 14, plunger 43 is provided with a recess 53 which receives a spring loaded locking pin 54 when the plunger is retracted to a predetermined position. Pin 54, normally biased inwardly by a suitable spring, extends inwardly through a suitable flanged opening in body 42 and rides on the outer surface of plunger 43. As plunger 43 is retracted against the force of the spring to a predetermined position, pin 54 engages recess 53 to lock the plunger in this retracted position.

A hydraulic cylinder 55, as shown schematically in Fig. 9, is employed to move the sheet carriers 16 on track

14. Cylinder 55 is secured to outer rail 29 at a position about one-quarter of a revolution from the low end of track 14. An oil reservoir and suitable operating mechanism for actuating cylinder 55 is indicated generally by 56.

To permit cylinder 55 to pivot as the cylinder drives the carriers 16 along the helical track 14, the lower end of cylinder 55 is pivotally attached to the inward flange of outer rail 29, as indicated by 57.

Cylinder 55 is normally biased toward outer rail 29 by a leaf spring 58 which is secured to rail 29. A piston rod 59 extends from the upper forward end of the cylinder 55 and an L-shaped block 60 is secured to the working end of the piston rod 59. A feeder pawl 61 is pivotally attached to the outer extremity of block 60. Pawl 61 is adapted to engage the body 42 of sheet carriers 16 and moves the carrier upwardly on track 14 as piston rod 59 is extended.

Piston rod 59 is guided in reciprocal movement by a grooved roller 62 which is rotatably secured to the underside of block 60 and is adapted to ride on the inwardly extending edge of outer rail 29 as the piston rod 59 is extended and retracted. Leaf spring 58 serves to maintain roller 62 in engagement with rail 29.

To move the sheet carrier 16 and the attached sheet 4, the feeder pawl 61 engages body 42 of the adjacent carrier 16, and as piston rod 59 is forced outwardly to its extended position, carrier 16 is pushed ahead of the rod along track 14. Movement of carrier 16 by cylinder 55 results in corresponding movement of the attached sheet 4 and the other carriers 16 which are also engaged with sheet 4. Pressure in cylinder 55 is then shut off and the piston rod 59 slowly returns to its retracted position. A holding pawl 63 is secured to outer rail 29 and is pivotally tripped by body 42 as the same moves upwardly and prevents the sheet carrier 16 from rolling downwardly on track 14 when piston rod 59 is retracted.

During return of the piston rod, feeder pawl 61 contacts the following sheet carrier, which has moved into the original position of the leading carrier, and the pawl is pivoted downwardly to enable it to pass therethrough. After pawl 61 has passed beneath the following carrier and returned to its upright position it will engage and move the following carrier upon forward movement of the piston rod 59.

It is desirable that the piston of the hydraulic cylinder 55 be spring returned and manually controllable by a suitable valve so that when the silo, after assembly, is backed down on track 14 onto the footing 3, as will be hereinafter described, the rate of retraction of piston rod 59 will be slow and steady to control the speed of back up.

The turntable 15, as shown in Figs. 6, 7, and 8, is disposed on grade level several feet above footing 3 to serve to support the coiled sheets 4 as the same are being fed onto the fixture 13.

Turntable 15 is rotatably mounted on a plate 64 which is supported on a pair of spaced horizontally disposed channels 65. Channels 65 are secured to adjacent outer supporting members 21 of fixture 13 and extend outwardly therefrom. Channels 65 are reinforced by diagonal braces 66 which are connected between channels 65 and members 21.

A bearing block 67 is secured and extends across the outer ends of channels 65 and a pair of threaded screw jacks 68 are engaged in suitable openings in the end portions thereof.

The lower ends of jacks 68 rest on a bearing channel 69 which is supported on the ground, and turntable 15 may be conveniently leveled by the threaded adjustment of jacks 68.

Sheets 4, in coiled form, are maintained in proper position on turntable 15 by a plurality of pneumatic industrial type wheels 70. A number of the wheels 70 are rotatably secured in a spaced relation on the circularly

spaced vertical shafts 71 which are attached to plate 64 and extend upwardly therefrom.

Shafts 71 with attached wheels 70 form a pocket into which the coiled sheets 4 are disposed in proper position for feeding onto the erection fixture 13.

A vertically disposed guide roller 72 is rotatably secured to an outer supporting member 21 approximately beneath the low point of the helical track 14. The lower edge of sheet 4 is adapted to ride on guide roller 72 and is supported by the roller as the sheet is fed onto the fixture 13.

As the leading end portion of the uppermost of the sheets 4 is cut on an angle or tapered to enable the top edge of the silo to lie in a substantially horizontal plane, a number of temporary sheet hangers 73 are employed to support the tapered end during the first convolution, as shown in Fig. 7. Hangers 73 serve to interconnect the sheet carriers 16 with the tapered portion of sheet 4.

The lower edge portion of each sheet hanger 73 is provided with a series of holes which are aligned with corresponding holes in the upper edge of the uppermost sheet 4. Suitable hooks 74 are employed to engage corresponding holes in sheet 4 and hanger 73 to removably secure the two sheets together.

The upper edge portion of each sheet hanger 73 is provided with a series of spaced holes which receive the outer end of studs 45 of carriers 16.

The sheet hangers 73 are a regular part of the erection equipment carried by the erection crew. The hangers 73 are provided with the proper curved contour for the silo and each hanger has a different and varying width to compensate for the varying width of the tapered portion of the uppermost sheet, to which the hangers are attached.

To begin assembly of the erection fixture 13, the base ring 17 is initially set in position on the annular footing 3 inside the radius on which the anchor bolts 7 are located.

The vertical supports 20 are then attached to the ring 17 and the rails 29 and 30 are properly secured to supports 20.

The center post 32 and umbrella ring 34 are assembled and positioned on the ground within footing 3. The assembly of fixture 13 is completed by the attachment of the radial supports 36 between post 32 and supports 20.

To begin erection, the uppermost of the metal sheets 4 of the silo is disposed in coiled form on turntable 15 within wheels 70. As shown in Figure 1 the silo is composed of four sheets 4, each of which is successively placed on turntable 15 in preparation for feeding the same onto the erection fixture 13.

Each of the sheets is designed with a thickness to withstand the internal pressure of the silage at the particular position in the silo at which the same is disposed. It is contemplated that for a silo having a diameter of about 20 feet the diameter of the largest coil will be less than six feet and the weight of the heaviest coil will be under 3500 pounds.

The sheets are cut to the proper angles, provided with the necessary bolt holes, glass coated and fired if desired and wound into a coil in the factory. The sheets are transported in the coiled form and lifted onto the turntable 15 by a suitable crane.

After the coiled sheet is placed on the turntable the straps containing the coil are cut and the free end of the sheet is drawn manually toward the low point of the track 14.

Sheet hangers 73 of the proper tapering width are then secured to the corresponding portion of the tapered leading end of the sheet 4.

A sheet carrier 16, disengaged from track 14, is thereafter secured to the first of the sheet hangers 73 which carries the sheet 4 by inserting the end of stud 45 through

one of the holes in the upper edge of the hanger. The plunger 43 of the sheet carrier 16 is then manually retracted within body 42 and locked in this position by pin 54. The pair of vertical rollers 49 of carrier 16 are then placed on the outer rail 29 and the inner roller 46 is snapped into position against inner rail 30 by withdrawing pin 54 from recess 53.

The first sheet carrier 16 is manually moved upwardly on track 14 with the coiled sheet 4 being unwound by the movement, and a second carrier 16 is similarly attached to sheet hanger 73 in a spaced relation thereon and mounted on track 14. Additional carriers 16 are mounted on track 14 and the preceding carriers are manually moved upwardly on the track with the bottom edge of sheet 4 riding on guide roller 72, until the first carrier rides past feeding pawl 61 of hydraulic actuator 55. At this point the pawl 61 will engage body 42 of the first carrier 16 and the sheets may then be moved upwardly on track 14 by means of the hydraulic cylinder 55.

As the sheet 4 and attached hangers 73 are moved upwardly on track 14 by cylinder 55 in a manner previously described, additional carriers 16 are continually attached to the following hangers 73 at the low point of the track.

At about the position of the first convolution, that is, when the first carrier 16 reaches the uppermost point of the track 14, the portion of sheet 4 approaching the lowermost point of the track will be of sufficient width to enable the carrier 16 to be attached directly to the sheet without the use of hangers 73.

After the first convolution is completed the first carrier 16 is withdrawn from the high point of track 14, disengaged from hanger 73 and reinserted at the low point of the track. This operation of removing carriers from the high point and reinserting at the low point is repeated until the entire silo is completed.

To reinsert the carriers 16 at the low point of the track, the outer end of stud 45 is initially inserted through a bolt hole adjacent the lower edge of the first convolution and the carrier 16 is then mounted on track 14. As the unwound portion of sheet 4 moves into a tangential relation with the first convolution the stud 45 is inserted through an aligned bolt hole in the upper overlapping edge portion of the sheet. Thus the second convolution will be disposed with its upper edge portion in overlapping relation with the lower edge portion of the first convolution and this overlapping arrangement is repeated throughout the structure so that each convolution will be outwardly offset from the preceding convolution and there will be no protruding ledges or ridges on the inner surface of the silo to obstruct the downward movement of the silage.

The bolt holes in the upper edge of each sheet 4 are spaced slightly farther apart than the holes in the lower edge portion thereof to compensate for the overlap of convolutions. In addition the spacing of the holes adjacent the upper edge of sheets 4 is varied to compensate for the different thickness of sheets 4.

As the unwound sheet comes into tangential relation with the first convolution and studs 45 of carrier 16 are inserted through aligned bolt holes, suitable smooth head glass-coated bolts are inserted through succeeding aligned bolt holes, not used for studs 45, in the lower edge of the first convolution and the upper edge of the sheet. Bolt holders may be employed to hold the bolts while the same are threaded down by suitable nuts on the outer surface to secure the respective edges together.

Thus as the sheet moves into tangential overlapping relation with the preceding convolution the bolts are inserted and tightened down to progressively secure the respective convolutions together.

If the silo is to contain silage which may emit juices it may be desirable to manually coat the helical and vertical edge portions of sheets 4 to be secured together with a mastic or other sealing compound. The mastic may be applied to the free lower edge portion of each convolution as the same moves beneath track 14 suspended from the carriers 16.

The wound and bolted convolution continues to move upwardly from the high point of the track as the feeding of sheet 4 onto fixture 13 continues. However, the completed convolution is then unsupported by any portion of the fixture 13.

After about two convolutions of the silo 1 have been completed, the top edge of the completed portion of the silo is in position for attachment with roof member 2.

To accomplish the attachment of roof member 2 a number of pie-shaped roof segments 75 having downwardly flanged outer extremities are disposed on umbrella ring 34 with the flanged extremities of the segments overlapping body portion of silo 1. Each segment 75 is then bolted to the body portion and a circular cap 76 is bolted to the inner extremities of the segments at the center of the silo. The attachment of the roof 2 is completed by securing a number of sealing strips 77 over the radial seams between adjacent segments 75.

After the attachment of roof 2, the feeding of the sheets and bolting of the completed convolutions is continued until the uppermost sheet has been completely fed into the fixture 13. At this time the second coiled sheet is placed on the turntable, unstrapped and manually fed to the low point of the track 14.

Sheet carriers 16 are engaged with the bolt holes in the upper edges of the second sheet and the sheet positioned so that its leading end is lapped over the trailing end of the first sheet to form a vertical joint therebetween. Bolts are then inserted through aligned holes in the lapped vertical ends and threaded down on the exterior of the silo by suitable nuts.

The second sheet is then wound into helical convolutions and the remaining sheets 4 are thereafter successively put on the turntable 15 and also wound about fixture 13 in the manner described above.

After the final sheet 4 has been wound into helical convolutions and bolted together to complete the body portion of the silo, the turntable 15 and any other external structure is disengaged from the fixture 13 and removed from the vicinity of the completed silo in preparation for backing the silo down onto the footing 3 which is several feet beneath the lower circular edge of the silo at the completion of erection.

The backing down is accomplished by manually disengaging the holding pawl 63 which normally engages the rear side of a sheet carrier body 42. The carriers 16 will then move downwardly on track 14 by gravity and the attached silo will correspondingly move downwardly in a helical or spiral manner. To control the speed of back-down the hydraulic cylinder 55 is moved to its extended position with feeding pawl 61 engaging carrier body 42 to remove the weight from holding pawl 63. The holding pawl 63 is then manually released. The carrier body 42 which bears on feeding pawl 61 will move downwardly with the pawl 61 as the piston rod 59 is retracted. It is desirable that the speed of retraction of piston rod 59 be variable so that the speed of backdown can be varied to allow for safe operation under all conditions.

About the time rod 59 has returned to its retracted position the next carrier 16 above has come into engagement with holding pawl 63 and the downward movement of the silo is halted until the rod 59 is again extended and feeding pawl 61 is brought into engagement with the held carrier to take the weight off holding pawl 63. The holding pawl 63 is then manually released and the silo again moves downward with pawl 61.

During the backdown operation the sheet carriers are progressively disengaged from the silo at the low point of the track 14 and reinserted into the bolt holes in the silo at the high point of the track until the silo has completed its downward movement and is in contacting relation with footing 3. At this time all the sheet carriers

16. are disengaged from the silo and bolts are inserted through the aligned holes from which the studs 45 were removed to completed the bolted attachment of the sheets 4.

The silo 1 is then leveled on footing 3 and clamped thereto by clamps 5.

After the silo has been backed down onto footing 3 and clamped thereto, the manway 10 is cut into the silo by any suitable means at a position slightly above the finished grade level. The erection fixture 13 is then disassembled and the various parts are removed from the interior of the silo through manway 10.

As the fixture 13 is encompassed by the completed silo, it is desirable to construct each of the elements of the fixture 13, such as vertical supports 20, center post 32 and radial supports 36, of a number of small pieces or sections so that the fixture may be readily dismantled after erection of the silo and withdrawn from the same through the manway 10. In addition, as the erecting equipment is to be utilized at various locations in the field for the erection of helical silos of the type described, it is essential that the equipment be of a small, compact, lightweight nature which may be conveniently handled, packed and assembled.

With the erection fixture 13 removed from the interior of the silo, the sections of the unloader track 8, trough 9 and skirt ring 11 are passed through manway 10 and assembled in proper position within the silo. The concrete supporting wall 12 is then poured.

To complete the structure the excavated earth is back filled around the exterior of the silo to grade level and within the central interior of the silo to the level of the track 8 and trough 9. If desired a concrete or metal floor may then be installed in the silo.

It is to be understood that the present invention is not limited to the erection of a silo or storage vessel from glass coated metal sheets, but instead the sheets may be composed of any material having the ability to be wound in coiled form and the strength, when helically wound into the shape of a vessel, to withstand the pressures of the contained material.

Various embodiments of the invention may be employed within the scope of the following claims.

I claim:

1. An apparatus for erecting the cylindrical body portion of a storage vessel from a coiled sheet of material which comprises, a supporting frame, a helical track carried by said supporting frame, sheet carrying means removably secured to the sheet and adapted to ride on said track for progressively unwinding the sheet from the coil and forming the same into a series of helical convolutions with the edge portion of one convolution being secured to the edge portions of the following convolution as each convolution is progressively completed, and means adjacent said supporting frame for rotatably mounting the coiled sheet to enable said sheet to be uncoiled by said sheet carrying means as the same moves on said track.

2. An apparatus for erecting the cylindrical body portion of a storage vessel from a sheet of material which comprises, a supporting member, a helical track carried by said supporting member, sheet carrying means removably secured to the upper edge portion of said sheet and adapted to ride on said track, and means for moving said carrying means on said track to progressively wind said sheet into a series of helical convolutions with the lower edge of each convolution being attached to the upper edge of the following convolution to provide an integral substantially airtight body portion.

3. An apparatus for erecting the cylindrical body portion of a storage vessel from a sheet of material comprising, a supporting member, a vertically disposed helical track carried by said supporting member and consisting of a single convolution, sheet carrying means removably secured to said sheet and adapted to move upwardly on said track, and means for moving said sheet carrying

means on said track to wind said strip into a series of helical convolutions with the first formed convolution moving upwardly out of contact with said track as the following convolutions are formed, the first convolution being secured to the second convolution as the second convolution is being formed and each additional convolution being secured to the preceding convolution as each additional convolution is formed until the entire body portion is constructed.

4. An apparatus for the erection of the cylindrical body portion of a storage vessel adapted to rest on a foundation from sheet material which comprises, a helical track, supporting means resting on said foundation to carry said track, sheet carrying means removably secured to the sheet and adapted to move on said track, and means carried by said track for moving said sheet carrying means upwardly on said track to progressively form said sheet into a series of helical convolutions and for moving said sheet carrying means downwardly on said track after said convolutions have been secured together into the form of an integral body portion to back said body portion down onto said foundation.

5. An apparatus for assembling a storage vessel having a cylindrical body portion formed of a helically wound sheet of material and a roof member to enclose the top of said body portion and a foundation to support said body section, said apparatus comprising, a helical track, supporting means resting on said foundation for carrying said track, a series of sheet winding members removably secured at spaced intervals to the upper edge portion of the sheet and adapted to move upwardly on said track, means for moving said members on said track to progressively form said sheet into a series of helical convolutions with the lower edge of each convolution being secured to the upper edge of the following convolution to provide an integral substantially airtight body portion, means disposed centrally of said body portion and attached to said track supporting means for supporting said roof member, said roof member being secured to the upper end of said body portion, and means for moving said members downwardly on said track after assembly of said body section and said roof to back said body section down onto said foundation.

6. A method of erecting the body portion of a storage vessel from a metal sheet comprising, introducing a sheet carrying member onto a helical track, engaging said carrying member with the upper edge portion of said sheet, moving said carrying member upwardly on said track to progressively wind said sheet into a series of helical convolutions, disengaging said carrying member from said sheet, and securing the lower edge portion of each convolution to the upper edge portion of the following convolution to provide an integral substantially airtight body portion.

7. A method of erecting the body portion of a storage vessel from a coiled sheet of metal comprising, mounting said coiled sheet on a rotatable means, engaging a sheet carrying member with the free end of said coiled sheet, introducing said sheet carrying member onto a helical track, moving said carrying member on said track to progressively unwind said sheet from the coil and form said sheet into a series of helical convolutions, disengaging said carrying member from said sheet, and securing the edge portion of each convolution to the adjacent edge portion of the following convolution to provide an integral substantially airtight body portion.

8. A method of erecting a storage vessel adapted to rest on a foundation from a coiled sheet of metal which comprises, introducing a sheet carrier onto the lowermost end of a helical track supported by said foundation, engaging the sheet carrier with the free end of said coiled sheet, moving said sheet carrier upwardly on said track to form said sheet into a helical convolution, removing the carrier from the uppermost end of the track, disengaging said carrier from said sheet, repeating the steps of inserting said carrier at the lowermost end of the track, engaging

said carrier with said sheet, moving said carrier upwardly on said track, removing said carrier from the uppermost end of said track until said sheet is formed into a series of helical convolutions, and securing the lower edge portion of each convolution to the upper edge portion of the following convolution to provide an integral storage vessel.

9. The method of erecting the body portion of a cylindrical storage vessel from a series of metal coiled sheets which comprises mounting the first of the series of coiled sheets on a rotatable means, engaging a sheet carrying member with the free end of the first coiled sheet, inserting said sheet carrying member onto a generally helical track, moving said carrying member upwardly on said track to progressively unwind said first coiled sheet and form the same into a series of helical convolutions, securing the lower edge portion of each convolution to the upper edge portion of the following convolution to form an integral section of the body portion, mounting a second of the series of coiled sheet on said rotatable means, securing the leading edge portion of said second sheet to the trailing edge portion of said first sheet, engaging a second sheet carrying member to said second sheet, inserting the second sheet carrying member on said track, moving said second sheet carrying member on said track to progressively unwind said second sheet and form the same into a

series of helical convolutions, and repeating the aforementioned operations with the remaining coiled sheets until the remaining sheets are wound in a helical manner to complete the cylindrical body portion of the vessel.

10. An apparatus for erecting the helical wound body portion of a storage vessel from a sheet of metal having a tapered leading end portion to permit the upper edge of the completed body portion to lie in a substantially horizontal plane and comprising, a supporting member, a helical track carried by said member, sheet supporting means removably attached to the tapered portion of said sheet, and conveying means removably secured to said sheet supporting means and adapted to move on said track to progressively wind said sheet into a series of helical convolutions with the lower edge of each convolution being secured to the upper edge of the following convolution to provide an integral substantially airtight body portion.
